[57] **CLAIM**

The ornamental design for a case for storing saddle blankets, as shown and described.

DESCRIPTION

FIG. 1 is a top plan view of a case for storing saddle blankets showing our new design;

FIG. 2 is a left side elevational view thereof;

FIG. 3 is a right side elevational view thereof;

FIG. 4 is a rear elevational view thereof;

FIG. 5 is a bottom plan view thereof;

FIG. 6 is a front elevational view thereof;

FIG. 7 is a perspective view thereof;

FIG. 8 is a perspective view of the interior of the case shown in FIG. 5; and,

FIG. 9 is a bottom plan view of a related embodiment of the case shown in FIG. 5; and,

FIG. 10 is a perspective view of the interior of the case shown in FIG. 9.
